Primary Examiner — Nathan M Johnston

(57) **CLAIM**

The ornamental design for a three-section toothbrush holder with detachable tray, substantially as shown and described.

DESCRIPTION

FIG. 1 is a top, front and right side perspective view of a three-section toothbrush holder with detachable tray, showing my new design;

FIG. 2 is a bottom side perspective view thereof;

FIG. 3 is a front elevational view thereof;

FIG. 4 is a back elevational view thereof;

FIG. 5 is a left elevational view thereof;

FIG. 6 is a right elevational view thereof;

FIG. 7 is a top plan view thereof; and,

FIG. 8 is a bottom plan view thereof.

1 Claim, 8 Drawing Sheets
